(57) **CLAIM**

The ornamental design for a diagnostic assay system, as shown and described.

DESCRIPTION

FIG. 1 shows a front perspective view of a diagnostic assay system showing our new design;

FIG. 2 shows a rear perspective view of the diagnostic assay system;

FIG. 3 shows a top view of the diagnostic assay system;

FIG. 4 shows a rear view of the diagnostic assay system;

FIG. 5 shows a left side view of the diagnostic assay system;

FIG. 6 shows a right side view of the diagnostic assay system;

FIG. 7 shows a front view of the diagnostic assay system; and,

FIG. 8 shows an underside view of the diagnostic assay system.

The broken lines immediately adjacent the shaded areas represent the bounds of the claim, while all other broken lines are directed to environment; the broken lines form no part of the claimed design.
